VEGETABLE SLICER

Thomas A. Killman and Robert T. Killman,
Nashville, Tenn.

Application December 13, 1935, Serial No. 54,164

3 Claims. (Cl. 146—168)

This invention relates to a device for slicing vegetables into attractive and useful forms.

An important object of this invention is to provide a device of this type which, by means of very simple adjustments and rearrangement of parts, is made capable of cutting vegetables into a variety of attractive and useful forms.

Another object of this invention is to provide a device of this character that is simple to operate and easy to keep clean. A further object of this invention is to provide a device of this character which may be easily and cheaply constructed of inexpensive materials and which may be packed into a very small space for shipping.

Referring now to the drawings, Figure 1 is a perspective view of a preferred form of our invention showing the vegetable pushing slide partly withdrawn and one of the cutting blades in a cutting position.

Figure 2 is a cross section view taken along a vertical plane through the line 2—2 of Figure 1 looking in the direction of the arrows.

Figure 3 is a cross section view taken along a vertical plane through the lines 3—3 of Figure 1 looking in the direction of the arrows.

Figure 4 is a cross section view taken along a vertical plane through the lines 4—4 looking in the direction of the arrows.

Figure 5 is a view of the guide member.

Figure 6 is a cross section view taken along a plane similar to Figure 4 except that the cutting blade in Figure 4 has been reversed end for end and top for bottom and the vegetable pushing member has been entirely withdrawn.

Figure 7 is a side view of a second cutting blade.

Figure 8 is an end view of the same.

Figure 9 is a plan view of our device with the second cutting blade in position and the guide member in position for cutting corrugated slices.

Figure 10 is a greatly enlarged cross section view taken along the line 10—10 of Figure 9 looking in the direction of the arrows.

Figure 11 is a greatly enlarged cross section view taken from the same point of the device but with the guide member and the vegetable placed in the position for cutting "shoe strings."

Referring now in more detail to the drawings the numeral 20 indicates a box-like frame member provided at one end with bracket engaging member 21 for removable engagement with the bracket 22 adapted to be secured to a wall or other suitable surface by means of screws 23. The frame 20 is made from a piece of sheet metal such as dairy tin, etc., by turning up sides along the lines 24 and 25 as shown. One end of the

trough thus formed is welded or otherwise suitably secured to the end piece 26 formed from somewhat heavier sheet metal and to which the member 21 is welded or otherwise suitably attached.

The floor of the frame 20 is partially cut away to form a rectangular opening extending from approximately the center of the frame lengthwise to the end which is attached to the member 26. Narrow ledges 27 are left on either side of the opening. A narrow strip of the metal 29 is rolled back upon itself to strengthen the portion 20a of the bottom of the frame which remains.

Spot welded or otherwise suitably attached to the two upturned sides of the frame are the guides or runners 28 (see Figure 6) made by turning up the edges of a narrow strip of metal. These runners have one end partially pointed as at 28a in order to make the replacement of the slide easier. Guided by the slide member 28 and sliding within the frame 20 is a vegetable pushing frame generally designated by the numeral 30. This frame is made up of two longitudinal channel shaped members 31 joined at one end by a channel shaped member 32 and at the other end by the handle support member 33. Member 33 has its ends turned down and is pivoted to the longitudinal members by rivets 34 so that the wooden handle 35 which is fastened to member 33 by a rivet 36 may be folded back into the device.

The longitudinal members 31 are further joined near their center by the pusher plate 37 and by the finger plate 38. The finger plate 38 is formed as shown from a piece of sheet metal into a plurality of downwardly turned fingers 39 separated by slots 40. The upturned ears 41 serve to attach this plate to the longitudinal members 31 either by spot welding or other suitable means.

A removable blade member 42 having two cutting ends, one, number 43 for the purpose of cutting thin slices and the other number 44 for cutting "French fries", is shown in Figures 1, 2, and 4 in the position for cutting "French fries" and in Figure 6 in the position for cutting slices. Member 42 is made from a piece of flat sheet metal by turning sides 45 down. The edge 44 is sharpened being beveled on the under side. A strip of metal 46 formed into the shape shown is welded at the points 47 to the blade member 42. The forward edges 48 of the strip 46 are sharpened to a knife edge. Notches 49 are provided in the end of side member 45 adjacent the edge 44. Notches 50 are provided at the ends of side pieces 45 adjacent the edge 43. Edge 43 is sharp-

ened to form a cutting edge. An emboss 42a is formed on the surface of the cutting member 42 near the edge 43 for the purpose of strengthening the cutting member 42 laterally. When in place 5 in the device in a position for cutting "French fries" the downwardly turned edges 45 rest upon the ledges 27 on the floor of the frame 20. The notches 49 in the ends of the sides 45 engage pins 50 located in the frame 20. Thus the blade is held at its cutting position and against movement in a vertical direction while the other end 10 of the cutting member bearing against the member 26 resists the thrusts due to cutting vegetables.

The blade may be removed by simply raising 15 the end 43 and sliding the notches 49 from engagement with pins 50 when the blade can easily be raised out of the device. This operation however, can only be performed, of course, when the frame 30 has been withdrawn from frame 20 sufficiently to allow the blade being raised. When the frame 30 is pushed fully into frame 20 the fingers 39 extend to a point slightly beyond the rear edge of strip 46, while the strip 46 extends 20 between the fingers 39 into the slots 40 which are cut deep enough to allow of this. The edge 44 of the blade 42 extends above the fingers 39 into the space between the upper surface of the fingers 39 and the lower edge of member 37. An 25 adjustable pan retaining member 51 formed as shown is slidably mounted in the guide member 52 which is attached to the under side of the floor of the frame 20.

The member 26 has a lip 53 formed on the lower 30 edge for the purpose of cooperating with member 51 in holding a pan 57. By sliding member 51 forward or back in its guide 52 pans of various diameters may be accommodated.

The operation of the device for cutting "French fries" is as follows: A vegetable 54 such as a 35 potato, etc. is placed between the cross members 32 and 37, the sliding frame 39 being drawn away so that the vegetable rests upon the floor 20a of the frame 20. The handle 35 is grasped in one hand while the other hand holds the vegetable in 40 place. By pushing the frame 30 inwardly to frame 20 the vegetable is forced on to the cutting blades by the cross member 37 and the fingers 39. The blade thus cuts from the vegetable several 45 pieces of substantially rectangular cross section as at 55. The fingers 39 serve to force these pieces entirely through the depending portions of the blade member until they fall into the pan 57. The remaining upper portion of the vegetable slides upon the upper surface of the cutting member 42. When the end of the stroke in this direction has been reached the movement of the frame 30 is reversed and is pulled out of the frame 20. Member 32 causes the uncut portion of the vegetable to slide back on the upper surface of the 50 cutting member 42 and to drop therefrom upon the floor 20a of the frame 20 whereupon the frame 30 is once more pushed back into frame 20 and the cycle of operation is repeated. If the long pieces 55 are removed from pan 57 and 55 several of them placed side by side on the floor 20a with their long dimension lying across the device, and the frame 30 forced inwardly the cutting edges 48 will cut the pieces 55 along planes normal to the long dimension of the pieces 55 so 60 as to form cubes or "diced" vegetable.

The preparation and operation of the device in cutting thin flat slices of uniform thickness is as follows: The same cutting member which was used in the cutting of "French fries", just 65 described, is used also in this operation. The

cutting edge 43 on the end opposite to the one used in cutting "French fries" is used. Assuming the device to be arranged for cutting "French fries" the operation of converting it for cutting thin flat slices or "chips" consists in removing the cutting member 42 from the frame 20 which is accomplished by withdrawing frame 30 from frame 20 about halfway. The end of member 42 nearest the wall bracket 21 is raised and at the same time the member 42 is moved rearwardly 10 toward the wall bracket 21 thus disengaging slots 49 from pins 50 whereupon cutting member 42 may be entirely removed from frame 20. Cutting member 42 is now reversed end for end and top for bottom and reinserted, the end with cutting edge 43 foremost, into frame 20 until slots 56 fully engage pins 50, when the end with cutting edge 44 is dropped into place so that the cutting member 42 rests upon the ledges 27. The device is now ready for cutting "chips". The vegetable 20 is placed between the cross members 32 and 37 of frame 30, resting on the floor 20a of frame 20. The frame 30 is moved back and forth as previously described, whereupon edge 43 cuts thin slices or "chips" which pass between cutting edge 25 43 and the rolled under edge 29 of floor 20a into pan 57 as before. In this operation, fingers 39 come into contact with cutting edge 43 thus insuring a clean cut with no tearing of the vegetable.

This completes the variety of cuts made by 30 the use of cutting member 42. The remaining cuts are made by the use of a second cutting member generally designated by the numeral 58 and shown separately in Figures 7 and 8, and in place in the device in Figure 9. This cutting 35 member 58 is substituted for the cutting member 42. By its use the so-called "criss-cross" or "lattice", the wavy "corrugated", and the "shoe-string" cuts are produced. In the production of the last two cuts a guide member is used in 40 conjunction with the cutting member 58. The floor 20a of frame 20 is pierced as shown in Figure 1 and Figure 9 with three pairs of spaced 45 holes or apertures, A, A'; B, B'; C, C'. A removable guide member 59 (shown separately in Figure 5) is made from a straight length of round wire or rod by bending its ends 60 at right angles to the main portion of the wire and parallel to each other as shown. The length of the member 59 is such that the ends 60 may be easily 50 inserted into and removed from any pair of holes A, A'; B, B'; C, C'. When thus placed the straight portion of guide member 59 lies in contact with the floor 20a of frame 20. In order to allow the frame 30 to pass guide member 59 55 as the frame is moved back and forth, notches 61, 62 and 63 are provided in certain of the fingers 39 as shown in Figure 3, so that the fingers 39 clear the guide member 59 regardless of which of its three possible positions in the 60 floor 20a of frame 20 guide member 59 may occupy. These three positions will be called:

The A position where the ends 60 of guide member 59 are inserted in holes A and A'.

The B position where the ends 60 are inserted 65 in holes B and B'.

The C position where ends 60 are inserted into holes C and C'.

The A position is provided simply as a convenient place to keep the guide member 59 when 70 not in use. In all the preceding operations namely, cutting "French fries", "dice" and "chips" the guide member 59 was not needed and was assumed to either occupy the A position as 75

shown in Figure 1 or to have been entirely removed from the device.

The cutting member 58 consists of two side members 64 similar in shape and size to the side members 45 of the cutting member 42 previously described. Side members 64 are provided with slots 65 and 66 similar to slots 49 and 56 of the side members 45 of cutting member 42. Joining the side members 64 is the corrugated blade member 67 sharpened to a knife edge at both ends. Member 67 is formed from a flat sheet of metal by running it through two intermeshing gear-like rolls.

For cutting the wavy or "corrugated", the "shoestring", or the "lattice" or "criss-cross" cuts the cutting member 42 is removed and replaced with cutting member 58 so that slots 65 engage pins 50 and side members 64 rest upon ledges 27. Guide member 59 occupies the A position. The vegetable is placed between cross members 32 and 37 of frame 30 which is moved forward and back one time. This operation causes blade member 67 to cut one slice from the lower side of the vegetable, the object being to leave a corrugated surface on the lower side of the vegetable. This corrugated lower surface is the starting point for each of the cuts now to be described.

In order to make the "criss-cross" or "lattice" cut the vegetable is simply passed over the blade member 67 a second time, first turning the vegetable slightly about a vertical axis. The height of the blade member 67 above the floor 20a is such that the corrugations cut through into the grooves made by the previous cut and thus produce the "criss-cross" or "lattice" cut.

In order to produce the "corrugated" or wavy cut the preliminary corrugated lower surface is first formed on the vegetable as previously described. Guide member 59 is then placed in the C position. In this position the guide member 59 lies opposite one of the upwardly curved portions of the corrugated blade member 67. The vegetable having the previously produced corrugated lower surface is placed between cross members 32 and 37 and upon floor 20a so that guide member 59 lies in one of the grooves in the corrugated under surface as shown in detail in Figure 10 and generally in Figure 9. When frame 30 is now pushed forward and with it the vegetable, the blade member 67 cuts a corrugated slice from the lower portion of the vegetable, in which slice the grooves and ridges in the upper surface, due to the guiding action of guide member 59, are all parallel to and interlocking with the grooves and ridges in the lower surface, thus producing the wavy, continuous corrugated slice.

In order to produce the "shoestring" cut, the preliminary corrugated lower surface is first produced as previously described. Guide member 59 is placed in the B position. In this position member 59 lies opposite a downwardly curved portion of blade member 67. The vegetable is placed between cross members 32 and 37 and upon floor 20a so that guide member 59 lies within one of the grooves in the lower corrugated surface as shown in detail in Figure 11. The height of the cutting member 67 above the floor 20a is, as previously stated, such that the downwardly curved portions of the blade are located slightly lower than the upper portions of the grooves in the lower corrugated surface of the vegetable so that the blade cuts through. In the position just described when the frame 30

and with it the vegetable 54 is pushed inwardly, the blade member 67, due to the guiding action of guiding member 59 cuts off the lower surface of the vegetable 54 into a number of shreds of substantially circular cross section, and at the same time leaves the lower surface of the vegetable corrugated in readiness for the next cut.

The cutting member 58 may be reversed end for end and top for bottom so that slots 66 engage pins 50 and used in this position to produce slices similar to those above described except slightly thicker due to the increased distance from blade 67 to the floor 20a when the cutting member 58 is reversed.

For cleaning purposes the frame 30 is entirely withdrawn from frame 20, the cutting members and the guide member removed thus allowing every part to be thoroughly cleaned.

For compactness in packing for shipment cutting member 42 is placed in its operating condition, handle 35 is folded back into the device as shown by the dotted lines in Figure 4. Guide member 59 is placed in the C position and cutting member 58 is placed in the space between the lower edges of side members 31 and the floor 20a directly under the folded back handle 35.

Various modifications of the arrangements disclosed herein come within the purview of this invention, the scope of which is limited only by the appended claims.

We claim:

1. In a vegetable slicer, a stationary frame having a horizontal vegetable supporting floor, a main cutting blade carried by said stationary frame and lying in a plane parallel to and above said floor, a plurality of spaced vertical blades extending downwardly from the main cutting blade, a movable frame slidable within said stationary frame, composite vegetable pusher means carried by said movable frame and comprising an upper flat pusher strip mounted transversely of said movable frame and positioned entirely above the main cutting blade in a plane perpendicular to the plane of said blade and parallel to its cutting edge, and a second lower strip mounted transversely of said movable frame and lying in a plane parallel to and below the main cutting blade and spaced vertically from the upper flat pusher strip, said second lower strip being formed with slots, the ends of the metal between the slots being bent into a vertical plane, said plane being the plane that includes the upper flat pusher strip, whereby, at the end of a cutting stroke the main cutting blade passes into the space between the upper and lower strips and the vertical blades pass into the slots formed in the lower strip, and the bent down portions between the slots force the cut portions of the vegetable entirely clear of the blades.

2. In a vegetable slicer the combination with a frame having parallel side bars and a floor plate, a reversible cutting member formed with depending side flanges fitted between said side bars, slots formed in the ends of said side flanges, and pins in said side bars for engaging the slots on one end of the cutting member, said cutting member being capable of being reversed in position so that said pins engage the slots on the other end of said cutting member, cutting edges formed on each end of said cutting member, a strip bent to a zig-zag or serpentine form affixed to one end of the cutting member, said strip having a plurality of vertical portions, a plurality of upper horizontal portions and a plurality of lower horizontal portions, the upper horizontal portions being af-

fixed against the underside of one end of the cutting member, the vertical portions of said strip being formed into cutting edges, and the lower horizontal portions of said strip lying in a plane below the plane of said floor plate, when said cutting member is in such position in the frame as to put the cutting edge adjacent the zig-zag strip in operating position.

3. A cutting member for use in a vegetable slicer comprising a flat plate, depending side flanges carried by said plate, cutting edges formed

on each end of said plate, a strip bent to a zig-zag or serpentine form affixed to one end of said plate, said strip having a plurality of vertical portions, a plurality of upper horizontal portions and a plurality of lower horizontal portions, the upper horizontal portions being affixed against the underside of one end of said plate, the vertical portions of said strip being formed into cutting edges.

THOMAS A. KILLMAN. 10
